A. G. KESSLER

FLUID CIRCULATING PLATE

Original Filed Aug. 20, 1925

Inventor:
Armin George Kessler,
by Geyers Geyer
Attorneys.

UNITED STATES PATENT OFFICE.

ARMIN GEORGE KESSLER, OF BUFFALO, NEW YORK, ASSIGNOR TO FARREL FOUNDRY AND MACHINE CO., OF BUFFALO, NEW YORK, A CORPORATION OF CONNECTICUT.

FLUID-CIRCULATING PLATE.

Original application filed August 20, 1925, Serial No. 51,374. Patent No. 1,621,742, dated March 22, 1927.
Divided and this application filed June 14, 1926. Serial No. 115,858.

This invention relates to improvements in the steam or fluid-circulating plates which are employed more particularly in hydraulic presses for vulcanizing and similar uses.

5 This application is a division of my application Serial No. 51,374, filed August 20th, 1925, now Patent #1,621,742.

Its object is the provision of a simple and inexpensive plate of this character which 10 effectually provides for the uniform distribution of the heating or cooling fluid over its entire area, and which is so constructed that the fluid passages can be readily and thoroughly cleaned out in a minimum period 15 of time.

In the accompanying drawings: Figure 1 is a top plan view, partly in section, of one of the plates. Figure 2 is an end view thereof, the cover being partly broken away. 20 Figure 3 is a fragmentary transverse section on line 3—3, Fig. 2.

Similar characters of reference indicate corresponding parts throughout the several views.

25 In the preferred embodiment of the invention illustrated in the drawings, 10 indicates the plate which is rectangular in plan and made of rolled steel or similar material. Extending horizontally through the body of 30 the plate are a plurality of parallel circulating channels 11 formed by drilling through the plate from one end thereof to the opposite end. For the purpose of establishing communication between the several channels 35 to provide a circuitous course for the fluid through the same, their outer ends are connected by transverse ports or passages 12 disposed in the alternate spaces between the channels, as shown in Fig. 1. These ports 40 are preferably formed by planing or milling grooves or recesses in the opposite end walls of the plate between each pair of channels 11, the ports in one end of the plate being staggered with respect to those in the opposite end, whereby the fluid is caused to 45 circulate in a sinuous course cover the entire area of the plate.

The open ends and front sides of the channels 11 and ports 12, respectively, are closed 50 or covered by steel plates 13, which extend over the grooved ends of the plate and are

securely fastened thereto by bolts 14. These plates are preferably seated in corresponding recesses 15 and a suitable packing 16 of asbestos or copper is interposed between 55 each cover and the opposing side wall of the plate.

The outermost channel 11 at one side of the plate has a fluid inlet 17 while the corresponding channel at the opposite side of 60 the plate has a fluid outlet 19.

This improved steam plate is very easy to manufacture, its machining operations are few, and it can be produced at a moderate cost. Furthermore, the construction 65 and arrangement of the channels and ports materially facilitate the cleaning thereof from time to time, it being only necessary to remove the cover plate 13 for this purpose. 70

I claim as my invention:

1. A circulating plate of the character described, having a plurality of fluid-circulating channels extending through the same from one end thereof to the other and ports 75 formed by grooves cut in the opposite ends of the plate transversely of and connecting each pair of channels, a cover plate extending substantially the full width of the circulating plate and closing the ends of said 80 channels and the open sides of said ports, and means for detachably holding said cover plate in place.

2. A circulating plate of the character described, having a plurality of fluid-circulating channels extending through the same from one end thereof to the other and having a common inlet and a common outlet, transverse grooves in the opposite ends of the plate arranged alternately between each 85 pair of channels, and cover plates applied to the grooved ends of the circulating plate for closing the ends of said channels and the open sides of said grooves, each cover plate extending transversely of the circulating 90 plate over the corresponding ends and sides of the several channels and grooves, respectively.

3. A circulating plate of the character described, having a plurality of fluid-circulating channels having a common inlet and a common outlet and a recess in two opposing 100

end walls thereof, the channels opening into said recesses, transverse grooves in the bottoms of said recesses forming connecting ports between said pair of channels, the grooves at one side of the plate being staggered with respect to those in the opposite side, cover plates seated in the recesses for

closing the ends of said channels and the open sides of said grooves, each cover plate being common to the several channels and grooves opening in the corresponding recess, and means for detachably securing said cover plates in place.

ARMIN GEORGE KESSLER.
